No. 857,161.

PATENTED JUNE 18, 1907.

W. M. CUMMER.
MECHANICAL DRIER.
APPLICATION FILED FEB. 15, 1907.

UNITED STATES PATENT OFFICE.

WILLIAM M. CUMMER, OF CLEVELAND, OHIO.

MECHANICAL DRIER.

No. 857,161.

Specification of Letters Patent.

Patented June 18, 1907.

Application filed February 15, 1907. Serial No. 357,596.

To all whom it may concern:

Be it known that I, WILLIAM M. CUMMER, a citizen of the United States, residing at Cleveland, in the county of Cuyahoga and State of Ohio, have invented certain new and useful Improvements in Mechanical Driers; and I do declare that the following is a full, clear, and exact description of the invention, which will enable others skilled in the art to 10 which it appertains to make and use the same.

My invention relates to mechanical driers comprising a revolving drying cylinder through which the material to be dried passes 15 in one direction and the heated drying medium passes in the opposite direction, and the invention consists in a cylinder constructed in differential sections, all substantially as shown and described and particularly pointed out in the claims.

In the accompanying drawings, Figure 1 is a longitudinal section of the machine or drier, and Fig. 2 is a cross section thereof. Fig. 3 is an enlarged cross sectional view at 25 one of the joints of the sections.

I am aware that drying machines or mechanical driers, employing revolving or rotary drying cylinders are not at this time broadly new, and that in fact many machines 30 have been patented and are in common use, and hence I lay no claim herein to originality or novelty in so far as such machines broadly considered are concerned. But I am not aware that any one has ever before known or 35 used a machine constructed on the lines of the present invention and in which there are features and details of novelty as will now appear. Thus, the drying cylinder C is shown as constructed not only in sections 1, 40 2, 3 and 4 respectively, but the said sections are differential in size or cross section, and each section is of the same cross-sectional area from end to end. The smallest section is at the head of the machine where the raw 45 material to be dried enters and where it is exposed to the direct heat of the furnace, F, as it issues through furnace outlet. The first and smallest section is thus exposed both externally and internally to the greatest heat 50 of the furnace, and where said heat can be made most effective because the material enters both wet and cool, and needs to be placed in a condition to give up its moisture and dry as speedily as possible.

55 By making the cylinder in graduated sections as to cross section and by having the

sizes to vary relatively about as shown, I am enabled, first, to obtain an annular off set or shoulder at each joint between sections which affords room to interpose a strong connecting 60 ring G, and to provide openings for the admission of the products of combustion and air at suitable intervals into the cylinder without perforating the wall of the cylinder for this purpose. The shape of said connecting ring may vary considerably and be equivalent to the form shown, but a convenient form or shape is shown in cross-section and provided with a series of preferably oblong openings 6 in its web or middle portion. The 70 said openings or holes serve to admit the products of combustion from the furnace to the cylinder, whence said products flow to the mouth of the cylinder and are drawn off by means of the usual suction fan or blower 75 located in or above chute 7.

The special form of ring G shown herein has the advantage of furnishing two parallel surfaces extending in opposite directions and sufficiently spaced apart to rivet the cylinder sections thereon, and the further advantage of affording draft or suction openings which are above the plane or surface of the larger section into which the material is carried from the preceding and smaller section, so that a wall is formed about each opening 6, and especially at the bottom thereof, which will prevent crowding of the material out through said openings when the feed thereof throughout the cylinder may be slow 90 and there is disposition for it to pile up in the cylinder, more or less. This construction prevents loss of material through draft and suction holes 6 and avoids necessity of screens over said holes.

95 It is particularly important that the products of combustion and air should have free admission to the cylinder entirely around the same and particularly to the first section thereof, and that it should enter freely about the sides and top of same where there should be no obstruction, and this advantage is obtained in this construction because the holes 6 are so disposed and are so related to the walls about the cylinder that the inlet 100 through the same is especially effective at the sides and top of the cylinder. This advantage is further promoted and obtained in this invention especially by reason of the differential sizes of the cylinder sections. 110 Assuming that we have the usual drier wall inclosing the cylinder in which the top and

bottom are parallel and horizontal, it will be seen that the first and smallest section of the cylinder comes about into the center of the drier space with such ample room about its top and sides that it is completely enveloped in the heat. Obviously this could not be realized if the cylinder were of the same diameter throughout its length and came so near to the wall at its sides and top all along as to largely cut these portions off from exposure and confine the draft mostly to the bottom of the cylinder. The next result of this difference is that this style of cylinder in such settings as these will dry much more material in a given time and with given heat units than is possible in a straight cylinder or one which cuts off the side and top heat exposure in the fore part or end of the cylinder as a straight cylinder does.

20 Details of construction are the gear 9 about the rear end of the cylinder through which power is applied thereto to rotate the same in its supporting rollers 12, and discharge openings 14 are formed in the rear end 25 of the cylinder inside its closed end or head 15. Lift blades or ribs 16 run lengthwise of the cylinder sections. The front cylinder section is provided with a special bearing head H, which has a tire 10 about the same 30 running on rollers 12 and has an inwardly projecting annular neck 16 in a flange 17 to which section 1 of the cylinder is secured. At the rear end there is a head J, having tire 18 about the same running on rollers 12, and 35 carrying head 15 of the cylinder and last cylinder section 4.

Obviously the details of construction just described, and in fact all others, may be modified more or less and remain within the 40 spirit and object of the invention.

A series of openings 20 in flange 17 of bearing head H admit the heat at the very front of cylinder C and immediately about the discharge neck of chute 7.

45 What I claim is:

1. As a new article of manufacture, a drying cylinder formed in sections, and rings connecting the sections provided with openings transversely through the middle thereof, 50 whereby draft passages are formed into the cylinder.

2. A drying cylinder formed in sections of different sizes, and rings uniting adjacent ends of said sections equal to the difference in

the sizes thereof and provided with openings 55 into the cylinder.

3. A drying cylinder formed in sections and the end of one section smaller in diameter than the end of the adjacent section with which it connects, and rings connecting said 60 adjacent ends having a series of holes about their middle portion.

4. In a drying apparatus, a rotary drying cylinder formed in sections arranged to discharge one into the other successively and 65 varying in cross sections, and rings connecting said sections having webs with openings through the same.

5. In a drying apparatus, a rotary drying cylinder formed in sections of different diameters and each section having a uniform diameter and said sections increasing in cross sectional area from one end of the cylinder to the other, and rings uniting said sections having holes through the same, whereby 70 draft inlets to the cylinder are provided.

6. In a drying apparatus, a cylinder adapted to be rotated and provided with an inlet at one end and a discharge at the other end, and said cylinder constructed of a series of 80 sections of different diameters and each section having the same diameter, and inlet openings for the products of combustion at the ends of said sections.

7. A drying apparatus comprising a cylinder 85 composed of sections of different diameters and substantially angle shaped rings connecting said sections having draft openings in the webs thereof.

8. A drying apparatus comprising a drier 90 chamber, in combination with a drying cylinder formed in sections of varying sizes smallest at the front end of the cylinder, and a furnace at the front of said chamber adapted to discharge immediately beneath the 95 said smallest section of the cylinder.

9. A drying apparatus comprising a drying chamber of uniform depth from end to end, in combination with a drying cylinder largest at the rear formed of sections of increasing cross-sectional area from the front to the rear of said chamber.

In testimony whereof I sign this specification in the presence of two witnesses.

WILLIAM M. CUMMER.
